UNITED STATES PATENT OFFICE.

FREDERICK C. BOYNTON, OF MINNEAPOLIS, MINNESOTA.

MILL-STOCK MIXER AND DISTRIBUTER.

No. 882,925.

Specification of Letters Patent. Patented March 24, 1908.

Application filed August 8, 1907 Serial No. 387,592.

To all whom it may concern:

Be it known that I, FREDERICK C. BOYNTON, a citizen of the United States, residing at Minneapolis, in the county of Hennepin 5 and State of Minnesota, have invented certain new and useful Improvements in Mill-Stock Mixers and Distributers, of which the following is a specification.

My invention relates to devices for use in 10 flour-mills for mixing and distributing or feeding stock to the various machines.

The object of my improvements is to produce an apparatus that is capable of thoroughly mixing material or stock of different 15 kinds and discharging the mixture uniformly and in desired quantities.

My improved apparatus comprises a cylindrical casing containing series of revolving mixers or flights in radial arrangement, and 20 means for introducing material to the casing and for discharging it in regulated quantities. Such improvements are illustrated in the accompanying drawings, in which—

Figure 1 is a central vertical section of my 25 improved mixing and feeding machine; Fig. 2 is a horizontal section on the irregular line z—z of Fig. 1; Fig. 3 is a vertical section of the device for regulating the discharge of material; Fig. 4 is a horizontal section of the 30 same; and Figs. 5 and 6 are detail views of one of the flights.

In the drawings 1 designates the legs and 2 the cross-pieces of the supporting frame of the machine. On the top of the frame is a 35 short cylindrical casing 3 the bottom of which is secured to the frame by bolts 4. On the lower cross-piece is mounted, a driving-shaft 5 carrying a miter-gear 6; and above it is supported a spindle or vertical 40 shaft 7 having a miter-gear 8 in mesh with the gear 6. The spindle is supported by means of a collar 9 in contact with a boss 10 formed on a cross-piece 11 in which the spindle has a bearing; and the spindle also has 45 a bearing at 12 in the upper frame cross-piece. Power may be applied to the shaft 5 by means of a pulley and belt for rotating the spindle.

To the head of the spindle 7 is secured by 50 a set-screw 13 the hub 14 of a spider having a plurality of arms 15, preferably four, radiating from the hub. A series of flights or mixers 16 is formed on or attached to the under surface of each arm 15, preferably at 55 angles of about forty-five (45) degrees to the axis of the arm, with their lower ends ar-

ranged on a plane a short distance above the bottom of the casing. The flights preferably consist of flat blades having their upper portions contracted and provided with curved flanges 17 for the purpose of strengthening 60 the bases of the flights.

The top of the case consists of a fixed middle portion 18 and lids 19 hinged to its edges for providing convenient means for 65 access to the interior. The feed-spout 20 for supplying material to the machine is arranged to discharge at the center of the cover; and beneath its mouth is an inclined guide-trough 21 for catching the descending 70 material and properly delivering it to the mixers. This trough is preferably semi-circular and is attached by a fastener 22, or otherwise, over the center of the spider so as to revolve with the spider and deliver the 75 stock in a circular path coincident with the circle of action of the inner flights. By this arrangement an accumulation of stock at the center is avoided and the stock is subjected to the action of the mixers from the point of 80 admission throughout its travel to the sides of the case.

In the sides of the case are discharge openings 23 at any desired intervals, and connected with them are spouts 24 for conducting 85 the material to the proper machines for further treating it.

The quantity of stock fed from the machine into any of the spouts 24 is controlled by a feed-regulator. This regulator consists of a cylindrical body 25, which may be the upper portion of the spout 24, and having a tangential flange 26. The body 25 and flange 26 are preferably soldered or otherwise attached to a curved plate 27 which 90 may be secured to the case 3 at the sides of the openings 23 by screws or rivets 28 or in any desired way. A cover 29 at the top and a base 30 at the bottom of the flange 26 enclose the space between the flange and the 95 plate 27. An opening 31 in the cylinder 25 is provided for the passage of material from the case opening 23 to the discharge spout 24.

Within the body 25 is a short concentric cylinder 32 which has an opening 33 in its 105 side for the passage of material to the spout. This cylinder is open at the bottom and closed at the top by a cover 34 the rim of which seats on the upper edge of the body 25. This inner cylinder or tube is adapted to be 110 turned within the outer tube, and a handle 35 is provided on the cover 34 for that pur-

pose, to adjust the location of the opening 33 with reference to the opening 23 for regulating the discharge of stock. It is desirable to have the revoluble tube fit close enough within the fixed tube to be held in positions of adjustment by frictional contact, without the employment of a holding device. Such feed-regulator furnishes convenient and efficient means for regulating, or cutting off, the feed of stock from the machine to a discharge spout.

Having described my invention, what I claim and desire to secure by Letters Patent is—

- 15 1. A mill-stock mixer and distributer, comprising a casing providing a circular chamber having a plurality of outlets at its sides, means for introducing stock to the center thereof, a revolving spider therein having radial arms provided with flights adapted to work the stock from the center to the circumference, discharge spouts, hollow rotary valves having openings in their sides for controlling the passage of stock from said outlets to said spouts, and means for adjustably rotating such valves, substantially as set forth.
- 20 2. A mill-stock mixer and distributer, comprising a casing providing a revolving feed-trough for introducing stock in a circular path around the center of the chamber, a revolving spider in the chamber having radial arms provided with flights adapted to work the stock from the center to the circumference, discharge spouts connected with said outlets, and controllable valves therefor

for regulating the passage of stock through the outlets, substantially as set forth.

3. A mill-stock mixer and distributer, comprising a casing providing a circular chamber having a plurality of outlets at its sides, means for introducing stock to the center thereof, a revolving spider therein having radial arms provided with flights adapted to work the stock from the center to the circumference, discharge spouts, hollow rotary valves having openings in their sides for controlling the passage of stock from said outlets to said spouts, and tangential flanges and passage-ways for directing the stock to such openings, and means for adjustably rotating such valves, substantially as set forth.

4. A mill-stock mixer and distributer, comprising a casing providing a circular chamber having a plurality of outlets at its sides, means for introducing stock to the center thereof, a revolving spider therein having radial arms provided with flights adapted to work the stock from the center to the circumference, a feed-trough carried in inclined position by the spider for introducing stock in a circular path around the axis of the spider, and discharge spouts connected with said outlets, substantially as set forth.

In testimony whereof I have signed my name to this specification in the presence of two subscribing witnesses this 29th day of July, 1907.

FREDERICK C. BOYNTON.
